DESIGN.

—o—
J. WISHART.

CARPET.

No. 17,929.

Patented Dec. 6, 1887.

UNITED STATES PATENT OFFICE.

JOSEPH WISHART, OF NEW YORK, N. Y., ASSIGNOR TO THE BIGELOW CARPET COMPANY, OF CLINTON, MASSACHUSETTS.

DESIGN FOR A CARPET.

SPECIFICATION forming part of Design No. 17,929, dated December 6, 1867.

Application filed August 30, 1887. Serial No. 248,320. Term of patent 3½ years.

To all whom it may concern:

Be it known that I, JOSEPH WISHART, of New York city, in the county and State of New York, have invented a new and original Design 5 for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design. 15 My design is for a carpet-border. It has an inner ornamental margin. Its middle portion shows a half-panel or separated part, bounded partly by short right lines, with large circular flowers forming the rest of its border. Over 20 the interior of the panel are scattered small

flower-and-leaf forms and conventional ornaments. Between the successive panels are groups of conventional flower or leaf forms partly scroll-shaped in character, supported on stems, with a large circular flower below, 25 seen only in part. The surrounding spaces in this middle portion are ornamented with small flower-and-leaf and other forms. Above this middle part of the border is an ornamental band having a succession of crown-shaped figures. Beyond this is an outer ornamental margin. 30

What I claim as new, and desire to secure by Letters Patent, is—

The design for a carpet-border, consisting of 35 the design substantially as shown.

JOSEPH WISHART.
